UNITED STATES PATENT OFFICE.

CHARLES W. HUTCHINSON, OF ALLENDALE, NEW JERSEY.

SLEEVE-ADJUSTER.

No. 823,534.

Specification of Letters Patent.

Patented June 19, 1906.

Application filed October 25, 1905. Serial No. 284,279.

To all whom it may concern:

Be it known that I, CHARLES W. HUTCHINSON, a citizen of the United States, and a resident of Allendale, in the county of Bergen 5 and State of New Jersey, have made and invented certain new and useful Improvements in Sleeve-Adjusters, of which the following is a specification.

My invention relates to an improvement in devices for adjusting the length of sleeves of shirts, shirt-waists, boys' waists, and similar garments, the object being to provide means whereby the length of the sleeve may be shortened at will and in such way that the 10 folds or puckering will in no way be noticeable or objectionable and not interfere with the fit and natural hang of the sleeve, such folds or gathers being formed at the upper end of the sleeve where not seen, thereby 15 improving the shape of the sleeve as it is shortened by throwing it on a curved line on the outside of the elbow rather than at the lower end, where it is liable to sag and interfere with the natural set of the sleeve. 20 A further object of the invention is to provide means whereby the length of the sleeve may be properly adjusted, which means shall be attached or applied to the sleeve of the garment on the inner side thereof, so that it 25 will in no way detract from the neat appearance thereof.

A further object is to provide means for adjusting the length of the sleeve which shall be simple and cheap to manufacture and 30 which will not materially add to the expense of the garment and once attached thereto be practicable and durable, always remaining an active and reliable part of a garment as long as the same is wearable; and with these 35 and other ends in view it consists in certain novel features of construction, as will be hereinafter fully described, and specifically pointed out in the claim.

In the accompanying drawings, Figure 1 is 40 a view in elevation of a sleeve, a portion of which is broken away to show my improved means for adjusting the length thereof. Fig. 45 2 is a sectional view thereof. Fig. 3 is a similar view showing the sleeve shortened. Fig. 50 4 is a sectional view taken on the line 4-4 of Fig. 3. Fig. 5 is a sectional view taken on the line 5-5 of Fig. 2.

Referring to the drawings, 6 represents the 55 sleeve of a shirt, shirt-waist, or other similar garment, to the inner side of which is sewed, stitched, or otherwise secured a pocket 7, the

upper end of which is secured in the shoulder-seam 8, said pocket consisting of the rear part or portion 9 and the front or outer strip 10, the former preferably extending down to 60 the cuff 11 and the latter—that is, the strip 10—terminating at some distance above said cuff. Within this pocket is located the adjusting-tape 12, the upper end of which is secured in the lower or under part of the arm-size and to the top part of the sleeve running on a line with the under half thereof, thus preventing any strain or draw on the shoulder while being worn. To the lower end of the strip 9 is secured the socket-pieces 13 of 70 ball-and-socket fasteners, the ball members 14 being secured to the tape 12, any desired number of fasteners being employed. In the drawings I have illustrated six of the socket-pieces 13 and three ball members 14, the latter being separated by twice the distance between the socket-pieces 13 on the strip 9, so that when the tape is pulled downwardly in order to shorten the sleeve, as illustrated in Fig. 3, each ball member will register with a 80 socket-piece 13, the lowermost ball member 14 being hidden or concealed within the pocket when the sleeve is stretched to its normal length, as illustrated in Figs. 1 and 2.

In order to adjust the length of the sleeve, 85 it is simply necessary to give a slight downward pull to the end of the tape 12, causing the sleeve of the garment to fold or pucker at the upper end, where the same will be concealed or hidden from sight, and then to insert one or all of the ball members 14 in the proper socket member or members 13, thereby shortening the sleeve to the desired length. 90

It will of course be understood that I do not limit the application of the invention to 95 any particular garment, as it is applicable to the sleeve of a shirt, to boys' or ladies' waists, or other similar garments—in fact, to any article of clothing the length of which it is desired to adjust from time to time. It 100 will also be understood that my improved device, consisting of a tube or pocket of fabric, one side or portion of which is longer than the other, the longer side having secured thereto one member of a metallic fastener, 105 the said tube or pocket containing a tape, the free end thereof having applied thereto the other member of the fastener, may be made and sold entirely separate from any garment whatever, it being possible to at any 110 time apply the pocket by stitching or sewing the same to the garment, either when the

latter is being made or after being completed or finished.

I am aware that it is not new to construct a pocket containing an adjusting strap or cord, and hence I make no broad claim to such; but,

Having fully described my invention, what I claim as new, and desire to secure by Letters Patent, is—

10 A device of the character described, comprising a pocket made of fabric and stitched at its edges to the inner side of a garment, the fabric forming the rear side or portion of said pocket being extended at its lower end beyond that forming the front of said pocket, a tape contained within said pocket having its

upper end stitched to the upper end of said pocket, the lower end of said tape being free, and coöperating metal fastening devices, one member thereof being secured to the free end 20 of the tape and the other member to the elongated fabric forming the rear side of the pocket, substantially as described.

Signed at New York, borough of Manhattan, in the county of New York and State of 25 New York, this 23d day of October, A. D. 1905.

CHARLES W. HUTCHINSON.
